(57) **CLAIM**

The ornamental design for an inductor, as shown and described.

DESCRIPTION

FIG. 1 is a front view of an inductor according to the present disclosure.

FIG. 2 is a rear view of the inductor.

FIG. 3 is a left side view of the inductor.

FIG. 4 is a right side view of the inductor.

FIG. 5 is a top view of the inductor.

FIG. 6 is a bottom view of the inductor.

FIG. 7 is a first perspective view of the inductor.

FIG. 8 is a second perspective view of the inductor.

FIG. 9 is a cross section of the inductor taken along the line 9-9 in FIG. 5; and,

FIG. 10 is a cross section of the inductor taken along the line 10-10 in FIG. 5.

The Dash-Dash broken line portion of the figure drawings is included to show portions of the inductor that form no part of the claimed design. The Dash-Dot broken line portion of the figure drawings is included to show claim boundaries that form no part of the claimed design.
